UNITED STATES PATENT OFFICE.

JOSEPH C. BREINL, OF SAN FRANCISCO, CALIFORNIA.

VALVE

1,244,286.

Specification of Letters Patent. Patented Oct. 23, 1917.

Application filed May 24, 1916. Serial No. 99,848.

To all whom it may concern:

Be it known that I, JOSEPH C. BREINL, a subject of the Emperor of Austria, residing at San Francisco, in the county of San Francisco and State of California, have invented new and useful Improvements in Valves, of which the following is a specification.

The present invention relates to improvements in that class of valves which are raised from seats by the pressure of fluids flowing underneath the valve and raising them against a stop, and the primary object of the invention is the provision of a 10 guide plate, which, fastened to a center bolt, and welded to the valve plate, assures to the latter a lateral rigidity, and, by welding at points on the marginal section between connecting arms, permits the lift of the 15 valve plate to be sufficiently high without unduly straining the material, and also which, by being disposed between the valve plate and the stop plate, serves as a cushion to reduce the force of the impact at the end 20 of the lifting motion.

In the accompanying drawing, Figure 1 is a vertical section of one form of my invention; Figs. 2, 3, 4 and 5 are plan views of separate parts thereof; Figs. 6 and 7 are 25 sectional views on the lines 6—6, 7—7 respectively of Fig. 4 and Figs. 8, 9, 10, 11 and 12 are views similar to Figs. 1, 2, 3, 4 and 5 respectively of another form of the invention.

30 On referring to the drawing, it will be seen that my improved valve 1 comprises a valve seat V, a valve plate P, a combined guide and cushion plate G, a stop plate S, all of which are circular, a bolt B screwed 35 into the valve seat, a washer W on said bolt between the valve seat and the valve stop, and a nut N on said bolt. A dowel pin D through the parts S, W and V secures the 40 parts against relative rotation. The valve 45 seat V, of known form, has two concentric series of uniformly arranged seat openings o and a small threaded central opening c to receive the bolt B. The openings of each 50 series are separated from each other by 55 ribs r. The lower portions of said openings flare downwardly, as shown at z. Resting upon the valve seat is a circular sheet metal 60 valve plate P which is formed with a circular series of arcuate slots s registering 65 with the parts of the seat between the two 70 series of openings o therein, and with a large

central opening t and is spaced from the bolt B. G indicates a combined guide and cushion plate which is formed with a circular series of arcuate slots f and with a small central opening g to fit in a recess in the washer W. It has also a circular series of openings h between the central opening g and the arcuate slots f. The parts of the combined guide and cushion plate 60 between these arcuate slots f and between the openings h thus form arms a connecting the central and marginal portions of the guide plate. Said plate G is welded to the valve plate P at pairs of points p about midway between the outer portions of the arms a. The arms a are arranged tangentially, and this arrangement, together with the fact that the outer ends of said arms, being connected to the ring R midway between the welding points p, can themselves be raised from the valve plate P, permits the lift of the valve to be very great without undue strain upon the material bent by said lifting. The combined guide and cushion 70 plate is given a permanent bend out of the plane of the plate in the parts of the ring between the points where said ring is connected to the guide and cushion plate and also in the arms a. This permanent bend 75 provides a resilient connection between the periphery and the center of the guide plate and enables the springs necessary for closing the valve to be dispensed with or greatly reduced in strength.

90 In the open position of the valve, the guide and cushion plate fits closely against the flat surface of the valve plate and serves to cushion the valve at the end of its lifting motion and is interposed between the valve plate and the stop plate at the end of the ascent of the valve plate, and this is particularly the case because in operation the surfaces of the valve, cushion and stop plates are surrounded with lubricating oil 100 which acts as a buffer on the surfaces which approach each other. Since it is important to very carefully center the valve plate with reference to the valve opening, and since the guide and cushion plate is made out of very thin material, the hub of said plate is, as before referred to, centered in a recess of the lift washer W, and for the purpose of centering the guide and cushion plate still more accurately it may be welded to 105 said washer.

110 The stop plate S which limits the rising

inovement of the valve, is punched out of a sheet material, or is made of cast metal, and is otherwise formed similarly to said plate G except that it has a raised hub-like portion *j*. In this case arms *b* are arranged tangentially to avoid strain due to casting.

In the modification shown in Figs. 8-12, the valve seat is made with three concentric series of openings *o'* and the other parts are correspondingly formed except that the 10 guide and cushion plate G' is in the form of a ring R' having a central hub *h'* connected to said ring by tangentially extending arms *a'*. Said guide and cushion plate G' is 15 welded to the valve plate R' at points *p'* midway between the points of connection of the arms *a'* and also at points *u'* at the inner ends of inward extensions *e* from the ring. This construction is adapted for 20 larger valves. In this case also, it is desirable to provide recesses *v* to receive coiled springs *w* which are of a strength suitable for closing the valve on its seat. In this 25 form of the invention the parts of the ring between the welded points *p'* need not be 30 permanently bent, as in the form of the invention first described, since it is not necessary that the arms *a'* and the parts of the ring R' should have sufficient spring 35 force to press the valve to its seat, but this is effected by the coiled springs *w*.

I claim:

1. A valve comprising a valve seat, a 35 valve plate thereon, a guide plate of spring material secured to the valve plate, a stop plate, and means connecting said valve seat and stop plate, the outer portion of the 40 guide plate being secured to the valve plate at spaced points only thereof and the central portion of the guide plate being secured to the valve seat, said guide plate having parts connecting its central and marginal portions and openings between said 45 parts, said connecting parts being arranged obliquely to the marginal and central parts to permit a high lift of the valve plate from the valve seat.

2. A valve comprising a valve seat, a 50 valve plate thereon, a combined guide and cushion plate of spring material secured to the valve plate, a stop plate, means connecting said valve seat and stop plate, the outer portion of the guide plate being secured to the valve plate at spaced points 55 only thereof and the central portion of the guide and cushion plate being secured to the valve seat, said guide plate having parts connecting the central and marginal portions and openings between said parts, and 60 the marginal portions between said spaced points being set out of the plane of the remainder to give said first-named marginal parts an inherent resiliency tending to close the valve plate upon the seat plate.

3. A valve, comprising a valve seat, a

valve plate, a stop plate, means connecting said valve seat and stop plate, and a cushioning guide plate of spring material comprising a central portion secured to the valve seat, a peripheral ring attached at 70 spaced points only to the valve plate, and arms extending from the central portion of the guide plate and connected with said ring at points remote from its points of attachment to the valve plate, whereby said 75 arms move from the valve plate with a lifting motion, and said guide plate serves as a cushion and insures a parallel opening movement and lateral rigidity of the valve.

4. A valve, comprising a valve seat, a 80 valve plate, a stop plate, means connecting said valve seat and stop plate, and a cushioning guide plate of spring material comprising a central portion secured to the valve seat, a peripheral ring attached at 85 spaced points only to the valve plate, and arms extending from the central portion of the guide plate and connected with said ring at points remote from its points of attachment to the valve plate, whereby said 90 arms move from the valve plate with a lifting motion out of the plane of the remainder to give said lifting parts a spring tension tending to close the valve, and said guide plate serves as a cushion and insures a 95 parallel opening movement and lateral rigidity of the valve.

5. A valve, comprising a valve seat, a 100 valve plate, a stop plate, means connecting said valve seat and stop plate, a cushioning 105 guide plate of spring material comprising a central portion secured to the valve seat, a peripheral ring attached at spaced points only to the valve plate, and arms extending from the central portion of the guide plate 110 and connected with said ring at points remote from its points of attachment to the valve plate, whereby said arms move from the valve plate with a lifting motion, and said guide plate serves as a cushion and insures a parallel opening movement and lateral rigidity of the valve, and springs pressing 115 against the cushioning guide plate.

6. A valve, comprising a valve seat, a 120 valve plate, a stop plate, means connecting said valve seat and stop plate, and a cushioning guide plate of spring material comprising a central portion secured to the valve seat, a peripheral ring attached at 125 spaced points only to the valve plate, and arms extending from the central portion of the guide plate and connected with said ring at points remote from its points of attachment to the valve plate, whereby parts of 130 said peripheral ring disposed between the spaced points together with the connecting arms move from the valve plate with a lifting motion, and said guide plate serves as a cushion and insures a parallel opening movement and lateral rigidity of the valve. 135

7. A valve, comprising a valve seat, a valve plate, a stop plate, means connecting said valve seat and stop plate, and a cushioning guide plate of spring material comprising a central portion secured to the valve seat, a peripheral ring attached at spaced points only to the valve plate, and arms extending from the central portion of the guide plate and connected with said ring at points remote from its point of attachment to the valve plate, whereby parts of said peripheral ring disposed between the spaced points together with the connecting arms are set out of the plane of the remainder to give said lifting parts a spring tension tending to close the valve, whereby these lifting parts move from the valve plate with a lifting motion, and said guide plate serves as a cushion and insures a parallel opening movement and lateral rigidity of the valve.

8. A valve, comprising a valve seat, a valve plate, a stop plate, means connecting

said valve seat and stop plate, a cushioning guide plate of spring material comprising a central portion secured to the valve seat, a peripheral ring attached at spaced points only to the valve plate, and arms extending from the central portion of the guide plate and connected with said ring at points remote from its point of attachment to the valve plate, whereby parts of said peripheral ring disposed between the spaced points together with the connecting arms move from the valve plate with a lifting motion, and said guide plate serves as a cushion and insures a parallel opening movement and lateral rigidity of the valve, and springs pressing against the cushioning guide plate.

In testimony whereof I have hereunto set my hand in the presence of two subscribing witnesses.

JOSEPH C. BREINL.
